GAS BURNER AND SUPPORT

Minot R. Edwards, West Springfield, Mass., assignor to Springfield Burner Corporation, Springfield, Mass., a corporation of Massachusetts

Application December 7, 1949, Serial No. 131,548

5 Claims. (Cl. 158—115)

1

This invention relates to gas burners.

The invention is particularly concerned with a burner construction adapted to function either as a luminous flame type gas burner in which no air is premixed with the gas before ignition or as a blue flame type gas burner in which the gas and air are premixed at a point in the gas line some distance ahead of the burner proper.

The burner of this invention is adapted to be used either as an original installation or to effect the conversion of a coal or other type stove to a gas stove.

One of the objects of the invention is to provide a construction which will permit ready cleaning and servicing of the unit should it at any time become clogged. The burner ports are of small diameter and, accordingly, cleaning is occasionally necessary. Thus, the invention contemplates a construction permitting not only the removal of the burner from the stove but also the removal of a plug at the end of the burner to permit the introduction of a cleaning tool or brush.

Another object of the invention is the provision of a long tubular burner reenforced to such a degree by the heat radiating fins that vertical and horizontal distortion will be minimized.

Still another object of the invention is the provision of a supporting frame which will permit the burner proper to expand and contract longitudinally while lateral support at both ends is maintained.

These and other objects of the invention will become more apparent as the description proceeds with the aid of the accompanying drawings in which—

Fig. 1 is an end elevation of the burner mounted in a fire box.

Fig. 2 is a plan view of the burner.

Fig. 3 is a side elevation of the burner of Fig. 2.

Fig. 4 is a vertical sectional elevation on the line 4—4 of Fig. 2.

Referring to Fig. 1, a fire box is indicated at 2 and has positioned therein a support for the burner consisting of a base 4, a tubular column 6 carrying on its upper end a U-shaped bracket 8. The burner, indicated generally at 10, is supported by the bracket 8 and also by a metal baffle plate 12 which is designed to insure the upward movement of air through the burner passages only.

The burner comprises a long rectangular supporting frame 14 which supports the burner bar 16 at both ends. The supporting frame 14 has side flanges 18 and 20 which, when the burner

2

is in position, extend along the underside of the corresponding edges of plate 12. These flanges are secured to the plate by a plurality of bolts 22. The right hand end of frame 14, as viewed in Figs. 2 and 3, includes a cross-member having a circular opening therein forming a support 24 which is adapted to receive the corresponding circular end 26 of the burner bar 16. While the fit between end 26 and the circular support 24 is fairly close, nevertheless, there is sufficient play so that as the burner expands the end 26 may slide within the support.

At the other end of frame 14, it will be noted that the frame broadens slightly as at 28 and 30 to accommodate the larger burner base 32. This base end is affixed to the frame by screws 34 and 36 that pass laterally through the upwardly extending ears 38 and 40 of the supporting frame. It should be noted that screws 34 and 36 are above the level of the plate 12 and hence may be readily reached if it is desired to remove the burner from the frame without disturbing its mounting in the heat chamber.

The enlarged base 32 of the burner has a cavity or opening therein which connects with the gas line through a pipe or coupling 42. The opening in the base leads directly into the long tubular body 44 of the burner 16. This tubular body has a large number of small gas ports in its upper surface, a few of which have been indicated at 46. These ports are in the order of $\frac{1}{2}$ " in diameter, and therefore, in the drawing which is of reduced scale, they are shown merely as dots. In Fig. 4, however, the ports 46 have been exaggerated somewhat for the purpose of better illustration.

The right hand end of tube 44 is closed by a removable plug 45 which preferably will be screw-threaded and adapted to receive a key or screw driver to turn it when removal is desired. This plug, when removed, permits the insertion of a cleaning brush which may be run through the entire length of tube 44.

On the sides and bottom of the burner tube 44 are a plurality of radiating fins which are cast as an integral unit with the tube. These fins when viewed in Fig. 2 are indicated at 47 on one side and at 48 on the other. These fins merge with a continuous longitudinally extending fin 50 which can be plainly seen in Figs. 3 and 4. Longitudinal fin 50 gives substantial rigidity to the burner tube 44 against vertical distortion which is the direction in which distortion is most likely to occur as the top of the burner is normally somewhat hotter than the bottom.

The presence of plate 12 insures that the all upwardly moving air must pass the fins 47, 48, and 50 thereby providing for excellent radiation of heat from the burner tube. This radiated heat from the fins is in addition to the heat supplied directly by the burning gas.

A pilot 52 is provided which serves two purposes. One of the pilot flames 54 is aimed at the burner ports to cause ignition of the burner when gas is supplied thereto. The other pilot flame 56 is directed at a thermocouple 58 which controls the master valve so long as the pilot is in operation. When the thermocouple is heated, the valve will be open. Should the pilot flame go out and the thermocouple cool off, then the master valve will close and will be incapable of opening until the pilot is relighted. This is a safety device that is in common use on many types of burners and constitutes no part of the present invention.

When it is deemed necessary to remove the burner for any purpose such as cleaning, all that needs to be done is to remove screws 34 and 36 which being above plate 12 may be easily reached by a screw driver. The couplings to the burner pilot and thermocouple are likewise disconnected in the usual manner after which the burner unit may be raised upwardly at the rear end and then slid rearwardly to withdraw end 28 from socket 24. When this has been accomplished and the burner removed, the plug at the end of burner tube 44 may be unscrewed and the cleaning operation carried out. The reverse series of steps are then followed to restore the burner to operative position.

Immediately back of the pilot 52 is a vertical flange 60 which offers protection against drafts to the pilot. Flange 60 is also connected with a laterally extending block 62 on which is mounted the pilot 52, the gas supply coupling 64, and the thermocouple 58. A set screw 66 is utilized to maintain the thermocouple at proper elevation.

The burner bar and the fins are preferably made of cast aluminum although it should be understood that other suitable metals might be used.

I claim:

1. A gas burner for use in a gas burner assembly, comprising a burner bar in the form of a cylindrical hollow tube closed at one end by a removable plug, a plurality of gas ports along the top of said tube, a plurality of transverse radiating fins protruding laterally from the sides and bottom of said tube, a single vertical longitudinal fin at the bottom of said tube intersecting said transverse fins, all of said fins being integral with said tube, an enlarged base at the other end of said tube for connection with a gas supply, an integral laterally extending block between said transverse fins and said base, a pilot and thermocouple carried by said block, a supporting frame for said burner bar comprising side members extending along the side of said fins, an end cross member having a circular opening therein in which the plugged end of said tube is positioned, horizontal flanges along said side members adapted to be secured to a baffle, upstanding portions on said frame adjacent said enlarged base and means connecting said upstanding portions and enlarged base at a level above said horizontal flanges.

2. A gas burner for use in a gas burner assembly comprising a burner bar in the form of a cylindrical hollow tube closed at one end by a removable plug, a plurality of gas ports along the

5 top of said tube, a plurality of transverse radiating fins protruding laterally from the sides and bottom of said tube, a single vertical longitudinal fin at the bottom of said tube intersecting said transverse fins, all of said fins being integral with said tube, an enlarged base positioned on the other end of said tube and communicating therewith for connection with a gas supply, a supporting frame for said burner bar comprising side members extending along the sides of said fins, an end cross-member of said frame supporting the plugged end of said tube, horizontal flanges along said side members and means located above said horizontal flanges detachably securing said frame and base together.

3. A gas burner unit adapted to be installed in a stove, comprising in combination a tubular burner bar with radiating fins and an enlarged base at one end, an elongated vertically open supporting frame with its longitudinal elements close to and substantially parallel to a plane passing through the outside edges of said fins and having a cross member at one end shaped to support one end of said burner bar without longitudinal restraint, a pair of upstanding ears at the other end of said frame, means extending through said ears for detachably securing said enlarged base to said frame, and a horizontal flange on said frame below the level of said securing means and above the lower portion of said fins, said flange adapted to be fastened to a baffle plate whereby upon removal of said securing means the base end of said burner bar may be raised and the other end withdrawn from said cross member to permit complete removal of said burner bar from said frame.

4. A gas burner unit adapted to be installed in a stove, comprising in combination a tubular burner bar closed at one end and having an enlarged base for connection with a gas supply at the other end, a plurality of radiating fins connected to and extending crosswise of said burner bar, a longitudinally extending radiating fin connected to said burner bar and said crosswise extending fins, an elongated supporting frame with its longitudinal elements closely adjacent the opposite sides of said fins and having flanges along both sides for engagement with a baffle plate, a support at one end of said frame for holding the closed end of said burner bar in slidably engagement therewith, upstanding members at the other end of said frame and removable means passing through said upstanding members above the level of said flanges and securing said base to said frame.

5. A gas burner assembly comprising a straight cylindrical burner bar closed at one end and having an enlarged base at the other, a plurality of radiating fins integral with said burner bar, an elongated supporting frame with its longitudinal elements closely adjacent said fins and having a cross member at one end which includes a circular opening therein to receive the closed end of said burner bar in slidably engagement therewith, a baffle plate, means securing said frame in an opening in said baffle plate, said baffle plate closing the area around said frame, thereby compelling the passage of air through the space between said burner bar and said longitudinal elements, upstanding members at the sides of the other end of said frame extending above said baffle plate and removable connecting means extending through said upstanding members and securing said enlarged base to said frame whereby upon removal of said connecting means

said burner may be removed from said frame by raising said base vertically to a point above said frame and then withdrawing said burner in the direction of said base without disturbing said frame or said baffle plate.
